R. P. HEMMING.

RUG.

No. 16,709.

Patented May 25, 1886.

UNITED STATES PATENT OFFICE.

R. PAUL HEMMING, OF PHILADELPHIA, PENNSYLVANIA, ASSIGNOR TO
GEORGE W. ENNIS & CO., OF SAME PLACE.

DESIGN FOR A RUG.

SPECIFICATION forming part of Design No. 16,709, dated May 25, 1886.

Application filed April 10, 1886. Serial No. 198,508. Term of patent 8½ years.

To all whom it may concern:

Be it known that I, RICHARD PAUL HEMMING, a citizen of the United States, residing at Philadelphia, in the county of Philadelphia and State of Pennsylvania, have invented and produced a new and original Design for a Rug; and I do hereby declare that the photographic print accompanying this specification conveys to any one skilled in the art a clear understanding of the same, and is sufficient to enable such persons to use my invention.

The leading features of my design consist in a center medallion showing the representation of a stag's head, on the right a bugle, on the left a whip, and in the background water-plants, the whole surrounded by an ornamental border.

What I claim as my invention is—

The design for a rug, consisting of a center medallion showing a stag's head, a bugle on the right and a whip on the left, and water-plants in the background, the whole surrounded by an ornamental border, as shown in the photographic print.

R. PAUL HEMMING.
